CUTTERHEAD ASSEMBLY FOR CLIPPERS

Henry E. Meltzer, Racine, Wis., assignor to
All-Over Manufacturing Co., Racine, Wis.

Application January 24, 1947, Serial No. 724,158

11 Claims. (Cl. 30—196)

1

This invention appertains to electric hair clippers, dry shavers and the like and more particularly to novel means for releasably holding a cutter head assembly in operative position on the body of the clipper.

One of the primary objects of my invention is to provide a novel and simple mechanism whereby the cutter head assembly can be quickly removed from the clipper body by the mere pressing down on the forward end of the assembly in a direction opposite to the usual line of force on the assembly, when the clipper is in use, so that different sizes of cutter head assemblies can be quickly interchanged and cleaned.

Another salient object of my invention is to provide means for exerting a forward spring pressure on the cutter head assembly, so that upon downward rocking of the assembly to release the same from the body, the assembly will be automatically forced forward to a release disengaged position.

A further object of my invention is to provide a novel guide and latch plate carried by the clipper body for detachably receiving the tang of the cutter head assembly, the tank and latching plate being provided with an interengaging keeper slot and latch nose, means being provided on the latch plate for guiding the tang into proper latched position over the latch nose.

A further important object of the invention is to provide resilient means, including a spring retaining plate, for holding the tang over the latch nose and for forcibly urging the tang and cutter head assembly forward to a released position, when the cutter head assembly is manually rocked for lifting the tang and its keeper slot off of the latch nose against the tension of said spring retaining plate.

A further object of my invention is to provide novel means for forming the forward end of the guide and latch plate, whereby the forward end will form an effective support for the clipper head assembly, when the assembly is in its operative position on the clipper body.

A still further object of my invention is to provide novel means for forming and associating the spring plate support for the movable blade of the cutter head assembly and its guide and brace plate with the tang, whereby said plates will function to cooperate with the latch and guide plate and the spring retaining plate for facilitating the holding of the assembly in latched position and the releasing of the assembly when the same is manually rocked.

A still further important object of my invention

is to provide means for manually operating the spring retaining plate from the exterior of the clipper body for releasing the clipper head whereby the retaining plate can be either actuated by pressure on the clipper head or by actuating the manual means.

A still further object of my invention is to provide novel means for detachably connecting a cutter head assembly with a clipper body which will be durable and efficient in use, one that will be easy to operate and one which can be incorporated with a clipper body and cutter head assembly at a comparatively small cost.

With these and other objects in view the invention consists in the novel construction, arrangement and formation of parts, as will be herein-after more specifically described, claimed and illustrated in the accompanying drawings, in which drawings

Figure 1 is a fragmentary longitudinal sectional view through the forward end of a hair clipper showing one form of the novel means employed for releasably connecting a cutter head assembly with a clipper body, the section being taken substantially on the line 1—1 of Figure 2 looking in the direction of the arrows.

Figure 2 is a fragmentary side elevational view of a clipper constructed in accordance with my invention with parts thereof in section, the section being taken substantially on the line 2—2 of Figure 1 looking in the direction of the arrows, the view showing the clipper head assembly in its operative position on the body.

Figure 3 is a view similar to Figure 2, but showing the cutter head assembly rocked downwardly and the tang with its keeper slot lifted above the latch nose or dog.

Figure 4 is a detail side elevational view of the clipper head assembly removed from the body, parts of the figure being shown broken away and in section.

Figure 5 is a detail top plan view of the cutter head assembly removed from the clipper body, parts of this figure being shown broken away to illustrate structural detail.

Figure 6 is a fragmentary detail longitudinal sectional view through the forward end of the clipper body showing the novel guide and latch plate for the cutter assembly and the spring retaining and expulsion plate.

Figure 7 is a fragmentary longitudinal sectional view through the forward end of the clipper body, the view being taken at right angles to Figure 6 and showing the guide and latch plate and the spring retaining and expulsion plate in plan, parts

of the spring retaining and expulsion plate being shown broken away and in section.

Figure 8 is an enlarged fragmentary detail transverse sectional view through the forward end of the clipper taken substantially on the line 8—8 of Figure 2.

Figure 9 is a view similar to Figure 8, the section being taken on the line 9—9 of Figure 2 looking in the direction of the arrows.

Figure 10 is a view similar to Figure 1 but showing another preferred form of the invention, the figure being shown in section and taken substantially on the line 10—10 of Figure 11 looking in the direction of the arrows.

Figure 11 is a fragmentary side elevational view of the modified form of the clipper with parts thereof in section, the section being taken substantially on line 11—11 of Figure 10 looking in the direction of the arrows.

Figure 12 is a fragmentary sectional view similar to Figure 11 but showing the spring retaining plate moved to its inoperative position by its operating button.

Figure 13 is a top plan view of the cutter head assembly.

Figure 14 is a view partly in side elevation and partly in section of the cutter head assembly, the part in section being taken substantially on the line 14—14 of Figure 13.

Figure 15 is a fragmentary longitudinal sectional view through the clipper body, the cutter head assembly being removed from said body.

Figure 16 is a fragmentary sectional view taken substantially on the line 16—16 of Figure 15.

Figure 17 is a fragmentary transverse sectional view taken substantially on the line 17—17 of Figure 11 looking in the direction of the arrows and illustrating the means for adjusting the tension on the movable cutter blade.

Figure 18 is a fragmentary transverse sectional view taken on the line 18—18 of Figure 11 looking in the direction of the arrows.

Figure 19 is a fragmentary transverse sectional view taken on the line 19—19 of Figure 11 looking in the direction of the arrows.

Referring to the drawings in detail, wherein similar reference characters designate corresponding parts throughout the several views the letter C generally indicates the hair clipper and the same includes a cutter head assembly 10 adapted to be detachably connected with the clipper body 11.

The clipper body 11 can have its forward end open for receiving the cutter head assembly 10 and this body also receives the means for retaining the cutter head assembly in position and the mechanism (not shown) for operating the movable blade of the cutter head assembly.

The body 11 can be of any desired shape or form best suited for the purpose intended and can be made of upper and lower sections 12 and 13. The lower section includes a bottom wall 14 having its inner face formed substantially flat and smooth.

The cutter head assembly 10 includes the stationary cutter blade or comb plate 15 and the movable cutter blade 16. The blades are so formed and associated that the blade 16 is mounted for free movement back and forth over the blade 15.

In accordance with my invention I rigidly secure to the inner face of the stationary blade 15 a rearwardly extending tang 17 and it is to be noted that the tang extends substantially at an obtuse angle to the stationary blade 15. The for-

ward end of the tang is provided with an attaching foot 18 which can be riveted or otherwise fastened to the blade 15 as at 19. The foot 18 extends slightly forward of the rear edge of the stationary blade 15. The tang 17 adjacent to its rear end is provided with a centrally disposed keeper slot 20. This slot terminates short of the rear edge of the tang. Extending over the tang is a spring plate 21. This plate has formed thereon a pair of forwardly extending spring arms 22. The forward ends of the arms are in turn fastened to the movable blade 16 and function to hold the movable blade centered and down against the stationary blade 15. The spring plate 21 is provided with a guide and brace plate 23 and the plate 23 is fitted flat against the spring plate 21 and has formed on its side edges depending ears 24 for embracing the opposite sides of the resilient arms 22. The rear ends of the plates are rigidly secured to the tang on opposite sides of the keeper slot 20 by suitable fastening elements, such as rivets 25. The guide and brace plate 23 has also struck out therefrom a pair of spaced upwardly extending guide lugs 26, the purpose of which will be hereinafter set forth. The plates 21 and 23 have rotatably extending therethrough adjacent to their forward ends, an adjusting screw 27 which is threaded into a boss 28 struck up from the tang 17. Obviously, by adjusting the screw 27 up and down on the tang, the tension of the spring plate 21 can be adjusted for holding the movable blade 16 against the stationary blade 15 with varying pressures. Attention is directed to the fact that the rear edges of the tang and the plates 21 and 23 are beveled upwardly and forwardly as at 29 for a purpose, which will also later appear.

The means for releasably supporting the clipper head assembly 10 on the body 11 includes a combination guide and latch plate 30. This plate 30 is secured flat against the bottom wall 14 of the body, preferably by front and rear screws 31. The plate has struck up from its longitudinal side edges guide flanges or walls 32 and hence the plate 30 is of a somewhat U shape in cross section. The flanges 32 incline toward one another as they approach the rear edge of the plate and these flanges or walls 32 form a guide way for receiving the tang 17 of the clipper head assembly 10. The upper edges of the flanges 32 have formed thereon outwardly extending supporting flanges 33. These flanges 33 gradually incline upwardly from the front of the plate toward the rear of the plate. The extreme forward end of the plate 30 adjacent to its side edges has formed thereon forwardly projecting upwardly extending arms 34. The arms are so formed in conjunction with the plate to provide front and rear lugs 35 and 36. The outer side edges of the arms 34 also have formed thereon depending lugs 37. These arms are adapted to spring over and engage the attaching foot 18 of the tang 17 when the clipper head assembly is in its operative position on the clipper body and the lugs 35 engage over the front edge of the foot and the lugs 36 engage over the rear edge of the foot. The side lugs 37 engage over the end edges of the foot. The front edge of the plate 30 itself can be provided with a depending lug 38 for engaging against the rear edge of the foot and functions to limit the rearward insertion of the tang into the guide and latch plate 30.

The guide and latch plate 30 has formed centrally thereon the longitudinally disposed latch nose or dog 39 and it will be noticed that the nose 75 has its upper face inclined upwardly toward the

rear end thereof and that the extreme rear end of the latch nose has an abrupt shoulder 40.

Carried by the combined guide and latch plate 30 is a spring retaining and expulsion plate 41. This plate 41 is of a substantially U shape in plan and includes resilient side arms 42 and a connecting rear cross bar 43. The resilient arms 42 extend forwardly and downwardly and the front ends thereof are provided with attaching feet 44 which are rigidly fastened, such as by rivets 45, to guide and latch plate 30 directly in front of the inclined lateral flanges 33 of the guide and latch plate. Hence, the rear cross bar 43 extends transversely across the plate 30 directly in rear of the latch nose or dog 39. The resilient arms 42 normally hold the cross bar 43 with spring pressure down across the lateral flanges 33. The spring retaining and expulsion plate 41 also includes a centrally disposed resilient guide tongue 46 and this tongue is formed on the cross bar 43 and lies between the resilient arms 42. Struck out from the tongue is a depending teat 47 for a purpose, which will also later appear.

In associating the cutter head assembly 10 with the body 11, the tang 17 is slid into the body 11 and into the combined guide and latch plate 30. The converging flanges 32 function to guide the tang into position and to insure the aligning of the tang with the central axis of the body and as the tang is pressed inwardly, the tongue 46 will be received between the guide lugs 26 formed on the guide and spring retaining plate 23 and this further guides the tang in correct position and the lugs 26 prevent lateral shifting of the tongue 46. The beveled edges 29 of the tang and the plates 21 and 23 serve as means for gradually riding against the teat 47 to raise the spring tongue and the rear end of the spring retaining and expulsion plate 41 upwardly against the tension of the resilient arms 42. As the tang 17 rides over the latch nose 39 and the keeper slot 20 registers with the nose, the spring retaining and expulsion plate 41 will urge the tang downward with its rear end against the upper surface of the guide and latch plate 30. The latch nose being disposed in the keeper slot will now prevent forward movement of the tang and the cutter assembly. When the cutter assembly reaches its operative latched position, the arms 34 on the guide and keeper plate will snap over the foot 18 of the tang 17 and the cutter assembly will be firmly held in correct operative position on the clipper body 11.

If desired and preferred, the tang 17 adjacent to its forward end can be provided with depending headed rivets 48 and the heads of these rivets are adapted to ride on the upper face of the guide and latch plate and normally tend to hold the forward blade end of the cutter assembly 10 tilted upwardly. These rivets also function to eliminate objectionable friction between the tang and the guide and latch plate and act as spacers between the tang and guide and latch plate.

When it is desired to release the cutter assembly 10, it is merely necessary to grasp the clipper body 11 in the hand and press the thumb on the extreme front of the cutter assembly. By pressing downwardly with the thumb on the cutter assembly in the direction of the arrow shown in Figure 3, the cutter assembly will rock on the headed rivets 48, and the attaching foot of the tang 17 will swing away from the arms 34 of the guide and latch plate and the rear end of the tang will be elevated against the tension of the spring retaining and expulsion plate 41 above the

latch nose 39. The tension of the spring plate 41 increases as the same is forced upwardly by the tang and when the tang rides above the latch nose the teat 47 will engage the inclined or beveled faces 29 of the tang 17 and the plates 21 and 23. Consequently a forward spring thrust will be exerted on the clipper assembly and this combined with the downward pressure of the thumb will shoot or force the cutter assembly forwardly and out of the clipper body.

In Figures 10 to 19 inclusive, I have shown a simplified form of the invention, in which provision is made for manually operating the latching and releasing spring by means of a finger button or the like.

In this form of my invention, a clipper body or casing 49 is provided, preferably formed in upper and lower sections 50 and 51, so that easy access may be had to the operating mechanism (not shown). The forward end of the casing detachably receives and supports the cutter head assembly 52.

The lower section 51 of the casing at its forward end is provided with a pocket or chamber 53 for the reception of the retaining mechanism 54 for the cutter head assembly 52 and the retaining mechanism closes the lower end of the pocket or chamber 53. It is to be noted that the lower half section 51 of the casing can be provided with an upwardly and outwardly curved wall 55, which forms the top wall of the pocket or chamber 53. The pocket also opens out through the forward end of the body or casing 49 of the clipper.

Referring to the cutter head assembly 52, the same includes a stationary cutter or comb blade 56 on which is mounted for reciprocatory movement the movable cutter blade 57. Rigidly secured to the stationary blade 56 in the rear of the movable blade 57 is an attaching foot 58 carrying the angularly extending latching tang 59. The inner end of the tang 59 is preferably slightly curved upwardly as at 60 to form a guide face, the purpose of which will later appear. The tang itself is provided centrally with a slot 61 which forms a keeper opening. The opposite ends of the attaching foot 58 are bent at right angles away from the stationary blade 56 to provide guide and holding ears 62.

Arranged on the foot 58 is an angle bracket 63 and this bracket has rigidly secured to its outstanding flange 64 a substantially U shaped tension spring 65. The legs of the spring 65 carry the movable blade 57 and normally hold the blade down with proper tension against the stationary blade.

Means is provided for holding and adjusting the position of the angle bracket on the foot so that the tension of the opposite legs of the spring bearing on the movable blade can be adjusted. As shown, the lower flange 66 of the angle bracket rotatably receives adjusting screws 67 and these screws are threaded into the foot 58. The central portion of the foot has threaded therein an adjusting screw 68. By loosening the central screw 68 and by tightening or loosening either one or both of the screws 67 the angle bracket can be held straight and parallel with the foot 58 and at different levels thereto or tilted to one side or the other on the screw 68. This allows the desired tension to be given to the movable blade and more or less tension at the opposite ends thereof, as may be desired. If desired all of the screws can be adjusted outwardly so as to tilt the bracket on its rear edge, as shown in Figure 14.

The retaining mechanism 54 for the cutter head assembly 52 includes a main supporting plate 69. This plate can be secured to the lower surface of the casing 49 by means of fastening screws 70 and this plate closes the lower part of the chamber or pocket 53. As heretofore brought out. If desired, an ornamental cover plate 71 can be provided to go over the main supporting plate 69 and this cover plate can be held in place by the screws 70. The forward end of the main supporting plate 69 is provided with spaced parallel longitudinally extending slots 72 and the portion of the plate between the slots is bent downwardly and forwardly to provide an inclined guide tongue 73. Secured to the plate at its forward end is a bridge strap 74 and this bridge strap can be held in its desired spaced relation to the tongue 73 and the supporting plate 69 by shims 75. This forms a guide for the initial insertion of the tang into the supporting mechanism 54 and the bridge strap has formed on its rear edge an upwardly extending stop flange 76. The purpose of this flange is to prevent the inadvertent insertion of the tang into the pocket or chamber 53 above the bridge strap 74.

The plate 69 is reduced intermediate its ends and this reduced portion is provided with a pair of right angularly extending spaced parallel guide lugs 77. These guide lugs engage the side walls of the pocket and form a brace for the supporting plate 69 and prevents lateral shifting thereof. Formed on the plate 69 between the lugs 77 is the latch nose 78. The latch nose is provided with an upper inclined guide surface 79 and an abrupt lock shoulder 80. Riveted or otherwise secured at its rear end to the upper surface of the main plate 69 is a spring retaining plate 81. This spring plate 81 extends forwardly and upwardly from the rear end of the main plate 69 and extends over the latch nose 78. Secured to the spring plate 81 in rear of the latch nose is a finger button 82 and this button extends through guide openings 83 formed in the main supporting plate 69 and the cover plate 71. Hence by pressing inwardly on the button 82 the spring 81 can be flexed and moved away from the nose 78. The spring itself is preferably curved upwardly as at 84 beyond the button 82.

In use of this form of my clipper the cutter assembly head 52 is taken in the hand and the tang 59 is inserted within the supporting structure 54 between the bridge strap 74 and the guide tongue 73. The tang 59 will ride over the nose 78 and will push upwardly on the spring plate 81 and consequently the spring plate 81 normally functions to urge the tang downwardly. As the tang rides over the latch nose 78 the spring will force the tang downwardly and the latch nose into the keeper opening 61. This will securely lock and hold the cutter assembly on the clipper body 49.

To release the cutter head assembly, forward and downward pressure can be exerted on the tip end of the cutter assembly for rocking the tang on the guide tongue 73 against the tension of the spring plate 81. As the tang is raised above the latch nose 78 the spring plate will tend to force the tang forwardly and the cutter assembly can be instantly removed.

If so desired, the cutter assembly 52 can be released by placing pressure on the finger button 82 which will flex the spring so that the user can pull forwardly and downwardly on the cutter head assembly which will permit the removal of the assembly.

From the foregoing description, it can be seen that I have provided an exceptionally simple and rugged mechanism for detachably connecting a clipper head cutter assembly with a clipper body and one in which the assembly can be instantly released and projected from the body.

Various changes in details may be made without departing from the spirit or the scope of my invention, but what I claim as new is:

1. In a hair clipper, a body, a cutter head assembly, and means for detachably connecting the cutter head assembly with the body, said means including a combined guide and latch plate rigidly secured to the body, a tang rigidly connected with the assembly and movable into and out of latching engagement with the plate, said plate and said tang having interengaging latch and keeper means, a retaining and expulsion spring mechanism for guiding the tang into latching engagement with the plate and for holding the tang into latching engagement with the plate against the tension of the spring, the tang being rockable on the plate for movement out of latching engagement with the plate, said spring functioning to urge the tang and assembly away from the body when the tang is rocked from out of latching engagement with the plate.

2. In a hair clipper, a body, a cutter head assembly, and means for detachably connecting the assembly with the body including a combined guide and latch plate connected with said body, a tang carried by the cutter assembly movable into and out of the combined guide and latch plate, rearwardly converging upright flanges on the sides of the plate for guiding the tang into proper position on the plate, said plate having a latch nose and said tang having a keeper slot adapted to receive said nose, and spring means normally holding the tang down on the plate in latched position therewith, the tang being rockable on the plate against the tension of said spring means for moving the tang from out of latching engagement with said plate.

3. In a hair clipper, a body, a cutter head assembly, and means for detachably connecting the assembly with the body including a combined guide and latch plate connected with said body, a tang carried by the cutter assembly movable into and out of the combined guide and latch plate, rearwardly converging upright flanges on the sides of the plate for guiding the tang into proper position on the plate, said plate having a latch nose and said tang having a keeper slot adapted to receive said nose, and spring means normally holding the tang down on the plate in latched position therewith, the tang being rockable on the plate against the tension of said spring means for moving the tang from out of latching engagement with said plate, said tang having a beveled face against which the spring means is adapted to bear when the tang is rocked for pushing said tang forwardly.

4. In a hair clipper, a body, a cutter head assembly and means for detachably connecting the cutter head assembly with the body, said means including a combined guide and latch plate secured to the body, a rearwardly projecting tang having an attaching foot at its front end secured to the cutter assembly, said tang being movable into the plate, a latch nose on said plate and said tang having a keeper slot for receiving the latch nose, spring means carried by the plate for normally holding the tang in latched position with the nose, and forwardly

extending arms on said plate adapted to engage the foot when the tang is in latched engagement with the nose.

5. In a hair clipper, a body, a cutter head assembly, and means for detachably connecting the cutter head assembly with the body, said means including a combined guide and latch plate secured to the body, a rearwardly projecting tang having an attaching foot at its front end secured to the cutter assembly, said tang being movable into the plate, a latch nose on said plate and said tang having a keeper slot for receiving the latch nose, spring means carried by the plate for normally holding the tang in latched position with the nose, and forwardly extending arms on said plate adapted to engage the foot when the tang is in latched engagement with the nose, said tang being rockable on the plate against the tension of said spring means to a released position out of engagement with the latch nose and the arms, said spring urging the tang and cutter assembly forward when the tang is rocked to a released position.

6. In a hair clipper, a body, a clipper head assembly, and means detachably connecting the cutter head assembly with the body including a combined latch and guide plate rigidly secured to the body, a tang on said assembly projecting rearwardly therefrom movable into the plate, said plate having a latch nose provided with a front upwardly and rearwardly inclined face and rear abrupt stop face, said tang being slideable over the latch nose and having a keeper slot for receiving the nose, and spring means normally urging the tang down toward the plate and over the nose, said tang being rockable on the plate against the tension of said spring means for moving the tang from out of latching engagement with the nose and for increasing the tension of the spring, said spring bearing against the tang for pushing the same forwardly.

7. In a hair clipper, a body, a unitary cutter head assembly including a stationary blade and a movable blade, a rearwardly extending tang having a keeper opening adjacent to its rear end, a blade tension spring plate secured at the rear end thereof to the tang having forwardly extending resilient arms secured to the movable blade, a reinforcing plate fitted over the spring plate and secured at its rear end to the spring plate and the tang, said reinforcing plate having depending ears engaging the opposite sides of the spring plate adjacent to the rear ends of the resilient arms, means adjustably connecting the spring plate and the reinforcing plate to the tang, a combined guide and latch plate secured to the body for receiving the tang having a latch nose provided with a front rearwardly and upwardly inclined face and a rear abrupt face, the nose being received in the keeper opening upon the insertion of the tang into the plate, spring means normally urging the tang down over said nose, said tang being rockable on the forward end of the plate to move the tang from out of latching engagement with the nose against the tension of said spring means, the tang, spring plate and reinforcing plate having an upwardly and forwardly beveled face, said spring means being adapted to bear against said face upon the rocking of the tang to a released position from the nose, whereby said spring means will normally urge the tang forwardly of the combined guide and latch plate.

8. In a clipper, a body having a pocket in its forward end, a cutter head assembly, and

means for detachably connecting the cutter head assembly with the body including combined latch and guide plates rigidly secured to the body and closing the lower end of the pocket, a latch tongue on said plate, a tang rigidly secured to the cutter head assembly movable into the pocket over the plate and its latch nose, spring means carried by the plate for normally urging the tang into latching engagement with the nose, and a thumb button for moving the spring means from out of engagement with the tag.

9. In a clipper, a body having a pocket in its forward end, a cutter head assembly, and means for detachably connecting the cutter head assembly with the body including combined latch and guide plates rigidly secured to the body and closing the lower end of the pocket, a latch tongue on said plate, a tang rigidly secured to the cutter head assembly movable into the pocket over the plate and its latch nose, spring means carried by the plate for normally urging the tang into latching engagement with the nose, and a thumb button moving the spring means from out of engagement with the tang, guide lugs on the cutter head assembly for engaging the inner surfaces of the side walls of the pocket.

10. In a clipper, a body having a pocket opening out through its forward end, a cutter head assembly including a rearwardly extending tang having a keeper opening, and attaching foot on said tang rigidly secured to the assembly, guide lugs formed on the end of the foot, and means for detachably connecting the cutter head assembly with the body including a combined guide and latch plate rigidly secured to the body and forming the lower wall for the pocket, a latch nose formed on said plate, a forwardly and downwardly inclined guide tongue on the forward portion of said plate, a guide and bridge strap secured to the forward end of the plate in spaced relation to the tongue, said tang being insertable into the pocket and over the plate between the tongue and bridge strap, a spring normally urging the tang down against said plate whereby the latch nose will engage in said keeper opening when the tang is inserted to its full extent in the pocket, means for flexing the spring to move the same above the tang, and said guide lugs being adapted to engage the inner surfaces of the side walls of the pocket when the tang is inserted to its full extent in said pocket.

11. In a clipper, a body having a pocket opening out through its forward end, a cutter head assembly including a rearwardly extending tang having a keeper opening, and attaching foot on said tang rigidly secured to the assembly, guide lugs formed on the end of the foot, means for detachably connecting the cutter head assembly with the body including a combined guide and latch plate rigidly secured to the body and forming the lower wall for the pocket, a latch nose formed on said plate, a forwardly and downwardly inclined guide tongue on the forward portion of said plate, a guide and bridge strap secured to the forward end of the plate in spaced relation to the tongue, said tang being insertable into the pocket and over the plate between the tongue and bridge strap, a spring normally urging the tang down against said plate whereby the latch nose will engage in said keeper opening when the tang is inserted to its full extent in the pocket, means for flexing the spring to move the same above the tang, and said guide lugs being adapted to engage the inner surfaces of the side walls of the pocket when the tang is inserted to

11

its full extent in said pocket, and means for preventing the insertion of the tang above the bridge strap.

HENRY E. MELTZER.
